CABLE SEPARATOR AND HANGER

Everett F. Kelm, Corning, N.Y., assignor to Corning Glass Works, Corning, N.Y., a corporation of New York

Filed July 9, 1959, Ser. No. 56,709

Term of patent 14 years

(Cl. D26—10)

Fig. 1 is a front elevational view of a combined cable separator and hanger or similar article, showing my new design, the back being substantially a mirror image thereof;

Fig. 2 is a side elevational view.

I claim:

The ornamental design for a combined cable separator and hanger or similar article, as shown and described.
